UNITED STATES PATENT OFFICE.

WILLIAM H. MILLSPAUGH, OF SANDUSKY, OHIO.

INTERNAL-COMBUSTION ENGINE.

Application filed October 11, 1923. Serial No. 667,862.

This invention relates to two-cycle internal combustion engines of the reciprocating sleeve valve type.

The invention has for its salient object to 5 improve the operation of engines of the character described.

Another object of the invention is to provide a two-cycle engine of the type defined having the parts so constructed and arranged 10 as to secure a thorough scavenging connection and more complete and efficient combustion of the fuel.

Another and more specific object of the invention is to provide means for so operating 15 the sleeve with relation to the piston that the down stroke of the sleeve valve will be relatively slower than the up stroke thereby causing air to be admitted in the cylinder during the up stroke.

20 Another object of the invention is to provide an engine of the type described that is simple in construction and comprises few operative parts and can be economically manufactured.

25 Further objects of the invention will appear from the following specification taken in connection with the drawings, which form a part of this application, and in which

Fig. 1 is a longitudinal sectional elevation 30 of an engine constructed in accordance with the invention.

Fig. 2 is a longitudinal sectional elevation taken substantially at right angles to Fig. 1.

Fig. 3 is a transverse sectional elevation 35 taken substantially on line 3-3 of Fig. 1, and

Figs. 4, 5, 6, 7 and 8 are sectional elevations illustrating diagrammatically the relative positions of the operative parts of the 40 engine at different points in the cycle of operation thereof.

In these figures,—

Fig. 4 shows the parts at the beginning of the power stroke.

45 Fig. 5 illustrates the positions of the parts near the end of the power stroke when the exhaust ports of the sleeve valve are opening.

Fig. 6 shows the parts in a position slightly 50 in advance of the position shown in Fig. 5 and in which the exhaust ports are still open and the intake ports are open.

Fig. 7 shows the parts at the beginning of

the in or up stroke or compression stroke with the exhaust ports closed and the intake ports still open, and

55 Fig. 8 shows the parts with the exhaust ports still closed and the intake ports also closed, this being the portion of the cycle in which the compression starts.

60 The invention briefly described consists of an internal combustion engine comprising a cylinder, a working piston therein, and a sleeve valve reciprocable between the piston and cylinder. The sleeve valve is provided

65 with intake ports and exhaust ports and the sleeve and piston are so relatively arranged that on the down or power stroke of the piston, the exhaust ports of the sleeve valve will be opened to the exhaust openings in 70 the cylinder block as the piston approaches its lower or outer position and will remain open until after the intake ports have opened whereby air, preferably under compression, 75 will rush into the cylinder thereby scavenging the cylinder. The exhaust ports will close shortly after the intake ports have

opened thereby trapping air in the cylinder, which is compressed on the up stroke of the piston. The piston and sleeve valve connections are so constructed and arranged 80

that the down or out stroke of the sleeve valve, opening the intake ports will be relatively slow compared to the up stroke or in stroke during which the intake ports are 85 closed. Further details of the invention will appear from the following description.

86 Referring to the drawings, the engine illustrated is of the inverted head type and comprises a cylinder 10, a working piston 11 mounted in the cylinder and connected by a connecting rod 12 to the crank 13 mounted on a crank shaft 14.

90 Fuel is injected through an opening 15 in the cylinder head, this injection being preferably controlled by a governor and a separate fuel pump being provided for each cylinder.

95 A sleeve valve 16 of the reciprocating type is mounted between the cylinder 10 and the piston 11 and this valve is provided with a plurality of circumferentially arranged intake ports 17 and exhaust ports 18. The exhaust ports 18 are adapted to establish communication between the space within the 100 sleeve valve and the exhaust ports 19 formed

in the wall of the cylinder and communicating with an exhaust chamber 20 in the cylinder head.

The intake ports 17 are adapted to admit air from the interior of the crank case 21 into the cylinder in a manner hereinafter described.

The sleeve valve 16 is connected by a link 22 to a yoke 23 pivoted at 24 to a lug 25 formed on the interior of the crank case. In this yoke is mounted a sliding block 26 having journaled therein an eccentric 27 which in turn is mounted on the crank shaft 14. As the shaft rotates, the block will reciprocate in the yoke thereby giving a motion of translation to the sleeve valve in a manner hereinafter described.

As illustrated in Fig. 2, a pair of links 22 may be used to connect the sleeve valve 20 to a pair of yokes 23.

The operation of the construction above described will now be set forth. Fig. 4 illustrates the parts in the position taken at the beginning of the down or power stroke of the piston. In this figure, it will be noted that the intake and exhaust ports of the sleeve valve are closed.

When the parts reach the position shown in Fig. 5, which is approximately 23 degrees 30 in advance of the completion of the power stroke, the exhaust ports in the sleeve valve are beginning to open, while the intake ports are still covered by the piston.

In Fig. 6 the exhaust ports are still open 35 and the intake ports are being uncovered by the piston. At this period in the cycle the compressed air from the crank case or from the compressors, as desired, is entering the cylinder and is scavenging the cylinder, expelling therefrom the burnt gases.

In Fig. 7 the exhaust ports are closed and the intake ports are still open.

In Fig. 8 the intake ports have been closed thereby trapping the air in the cylinder and during the remainder of the up stroke the trapped air will be compressed by the piston.

It will be noted that the opening of the intake ports in the sleeve valve consumes a 50 greater time than the closing thereof or, in other words, the particular operative connections for the sleeve valve will give a slow downward movement to the sleeve and a quick return. The yoke and sliding block 55 arrangement is familiarly known as the Whitworth quick return yoke.

If desired, as above stated, the air in the crank case may be compressed on the down stroke of the piston thereby furnishing 60 compressed air for the cylinder and if this is done a valve 30 may be provided in the crank case, this valve opening on the up stroke of the piston and closing on the down stroke.

Although one specific embodiment of the

invention has been particularly shown and described, it will be understood that the invention is capable of modification and that changes in the construction and in the arrangement of the various cooperating parts 70 may be made without departing from the spirit or scope of the invention, as expressed in the following claims.

What I claim is:

1. A two-cycle internal combustion engine 75 comprising a cylinder having exhaust ports adjacent the inner end thereof, a piston operating in said cylinder, a crank shaft, a sleeve valve slidably mounted between the piston and cylinder and having exhaust ports, air 80 intake ports intermediate the ends thereof, and operative connections including a quick return yoke between said sleeve valve and the crank shaft so arranged that said sleeve valve will be given a relatively slow movement near the end of each outward stroke to open the exhaust ports and the air intake ports and will close the exhaust ports near the end of each outward stroke, and a relatively fast return movement during the inward stroke of the piston whereby air admitted under pressure will be entrapped in the cylinder.

2. In a two-cycle internal combustion engine, a cylinder, a piston operating therein, 95 said cylinder having an exhaust port, a sleeve valve slidably mounted between the cylinder and piston and having intake and exhaust ports therein, a crank shaft, a connecting rod between the crank shaft and piston and operative connections including a yoke connected to the sleeve valve and pivoted in the crank case, a block slidably mounted in the yoke and eccentrically mounted on the crank shaft between the 100 crank shaft and sleeve valve whereby the intake ports of the sleeve valve will be opened before the exhaust ports of said valve are closed and will remain open after said exhaust ports are closed.

3. A two-cycle internal combustion engine comprising a cylinder having exhaust ports adjacent the upper end thereof, a piston operating in said cylinder, a crank shaft, a sleeve valve slidably mounted between the piston and cylinder and having exhaust ports adjacent the upper end thereof and intake ports intermediate the ends thereof and operative connections between said sleeve valve and said crank shaft whereby 115 the exhaust ports of the sleeve valve will be opened and the intake ports of the sleeve valve will be opened before the exhaust ports are closed, both sets of these ports being open prior to the completion of the out 120 stroke of the piston and whereby the exhaust ports will be closed prior to the closing of the intake ports on the in stroke of the piston, said operative connections including a yoke pivoted on the crank case, a block slid- 125

able in the yoke, an eccentric journaled in the block and mounted on the crank shaft and a link connecting the yoke and sleeve valve.

5 4. A two-cycle internal combustion engine comprising a cylinder having exhaust ports adjacent the upper end thereof, a piston operating in said cylinder, a crank shaft, a sleeve valve slidably mounted between the piston and cylinder and having exhaust ports adjacent the upper end thereof and intake ports intermediate the ends thereof and operative connections including a Whitworth quick return yoke between said sleeve valve and said crank shaft whereby the exhaust ports of the sleeve valve will be opened and the intake ports of the sleeve valve will be opened before the exhaust ports are closed, both sets of these ports being open 20 prior to the completion of the out stroke of the piston and whereby the exhaust ports will be closed prior to the closing of the intake ports on the in stroke of the piston.

5. A two-cycle internal combustion engine comprising a cylinder having exhaust ports 25 adjacent the upper end thereof, a piston operating in said cylinder, a crank shaft, a sleeve valve slidably mounted between the piston and cylinder and having exhaust ports adjacent the upper end thereof and air 30 intake ports intermediate the ends thereof and operative connections including a quick return yoke between said sleeve valve and said crank shaft so arranged that said sleeve valve will be given a relatively slow movement near the end of each outward stroke to open the exhaust ports and the air intake ports and will close the exhaust ports near the end of each outward stroke and a relatively fast return movement during the upward stroke of the piston, whereby air admitted under pressure is entrapped in the cylinder. 35 40

In witness whereof, I have hereunto set my hand this 8th day of October, 1923.

WILLIAM H. MILLSPAUGH.
